LOCK-JOINT ROOFING

James Melville Ferguson, Denver, Colo.

Application July 21, 1942, Serial No. 451,686

4 Claims. (Cl. 108—7)

This invention relates to roofing material such as is commonly employed in roll, strip, or sheet form as an outer covering for roofs of buildings, either in single sheet thickness or in superposed layers constituting so-called "built-up" roofs, and has as an object to provide an improved form and construction for such roofing material.

A further object of the invention is to provide an improved construction of roofing material designed to facilitate sealing cooperation between cooperating margins of adjacent sections of such material.

A further object of the invention is to provide an improved construction of roofing material designed to obviate certain disadvantages of conventional material of similar type.

A further object of the invention is to provide an improved construction of roofing material particularly adapted for use in superposed layers for the development of smooth, durable, weather-tight, multiple-ply roofs.

My invention consists in the construction, arrangement, and combination of elements hereinafter set forth, pointed out in my claims and illustrated by the accompanying drawing, in which—

Figure 1 is a fragmentary, isometric view of a roof corner of a conventional building construction wherewith the improvements constituting my invention have been operatively associated, a flap element of the improved roofing material being shown bent away from the plane of the roof as it would appear during application of the material to the roof. Figure 2 is a fragmentary, isometric view of conventional roof construction illustrating, in somewhat exaggerated detail, the usual practice of overlapping adjacent margins of the material strip or sheet units to form water tight joints. Figure 3 is a cross section through a laminated or "built-up" roof developed through use of my improved roofing material. Figure 4 is a cross section transversely of a strip of roofing material embodying the principles of my invention, the mid-portion of the strip being broken away to conserve space.

As a weather-proof outer covering for roofs of many specific types and constructions, relatively flexible sheet or strip units of felted material suitably impregnated with bitumen, asphalt, and like oils, has come into general and wide-spread use. Such roof coverings are applied in certain instances as single layers of the material and in other instances as a plurality of superposed layers cooperating to form a laminated roof of "built-up" type, it being common practice in the construction of either type of roof to overlap adjacent margins of the material units in a given layer of the material in the manner shown in Figure 2 in an effort to adequately seal the joint between adjacent such units against the pen-

etration of weather therethrough, a suitable binder, such as tar, liquid asphalt, cementitious material, or the like, being inserted as a seal between the overlap portions of the adjacent unit margins. This conventional practice has a notable disadvantage deriving from the fact that the roofing material must be abruptly bent where one strip or sheet unit engages over the margin of an adjacent unit, as is clearly indicated in Figure 2, and though such material is characterized by considerable inherent flexibility and may be readily bent without damage to overlap in the manner shown in Figure 2, such material in place of a roof tends to lose some of its initial flexibility as it weathers and dries under the action of the elements and develops a degree of brittleness which results in cracking and fissuring of the material where bent to overlap along the edges of an adjacent unit, the impact effect of rain, hail, and wind, together with expansion and contraction of the material as a result of temperature changes, all serving to initiate and enhance the development of such cracks and fissures as the material becomes relatively more brittle, it being obvious that any cracks or fissures opening through the material units destroy the weather tight function of the covering. Various expedients have been employed in an effort to minimize the above-described disadvantage of the conventional material as commonly applied, but such expedients as have heretofore come into use have proved to be inadequate to the ends sought or impractical because of the increased expense of their use. To obviate the disadvantages above noted and to provide a construction and arrangement of roofing material susceptible of development in either strip or sheet form for convenient application as a weather-tight roof covering in either single or multiple layers, is the prime function and purpose of the invention as hereinafter set forth.

My improvement consists, simply, in forming the adjacent, cooperating margins of the sheets or strips of roofing material, during manufacture of such material, so that they may interengage to form a conveniently sealable joint having a thickness no greater than that of the body of the material and thus eliminate abrupt bends or offsets in the material as applied. The invention may be applied to any suitable specific arrangement and combinations of materials constituting a flexible sheet or strip having weather-proofing qualities, irrespective of the particular constituents or manner of their combination, conventional practice being to form such material by impregnating a felted web of suitable fiber with weather-proofing oils or admixtures and compacting the product through suitable rolls. The invention consists in forming a relatively deep groove or channel in and

opening marginally along one edge of the strip or sheet unit of the material and a corresponding tapered tongue along the opposite margin of the material unit, so that said tongue is adapted to engage in and substantially fill the groove or channel of an adjacent unit.

As shown in the drawing, the numeral 10 designates the web or body portion of a conventional strip or sheet of felted roofing material such as is commonly employed for the weather proofing of roofs, such material being characterized by a degree of flexibility such as will permit rolling and bending of the strip or sheet units wherein the material is produced. In the course of its manufacture, the strip or sheet unit of the roofing material is formed, by any suitable means, with a relatively deep, inwardly-tapered, notch or recess 11 opening through one side margin of the unit throughout the entire length of said margin and extending inwardly of the unit substantially one-third of the unit width. The intersection of the unit body portion by the groove or recess 11 results in the formation of relatively thin flaps 12 of the material disposed in spaced relation as defining walls on opposite sides of said groove or recess, which flaps 12 are relatively thin in section, highly flexible and hence susceptible of convenient bending relative to the body portion 10, and are each tapered to an approximate "feather-edge" along their free margins.

The margin of the body portion 10 opposite that intersected by the groove or recess 11 is reduced in thickness by any means suitable to such purpose to form a tongue 13 coextensive with the corresponding margin of the unit, which tongue 13 is so dimensioned, positioned, and contoured as to fit freely within and substantially fill the groove or recess 11 of an adjacent unit of the material, the tongue 13 preferably being slightly smaller than its associated recess 11 so as to provide a space about said tongue when engaged within a recess 11 wherein suitable cementitious or sealing material may be disposed to effectively weather proof the joint thus formed.

In the practical use of roofing material embodying the improvements shown and described, a first strip or sheet unit is secured in covering relation with a roof portion in any suitable or usual manner which leaves the upper of the unit flaps 12 free and unsecured, whereafter said upper flap 12 is bent upwardly away from the other or lower flap 12 and the thus exposed surface of said lower flap 12 is then coated with a suitable binder or cementing agent, whereupon the tongue portion 13 of a second strip or sheet unit is overlapped on the coated lower flap 12 of the first unit, the upper surface of said tongue portion coated with the binder or cementing agent, and the upraised upper flap 12 is pressed against and in covering relation with said tongue portion to complete an efficiently sealed joint, the tapered character of the tongue portion and associated flaps cooperating to produce a joint which lies flat and is entirely free from abrupt bends, shoulders, or offsets formed in the material constituting the roofing units. Figure 1 illustrates the manner in which a roof may be covered with a single layer or thickness of material embodying the improvements of the instant invention, and it will be immediately apparent that "built-up" roofs may be simply and conveniently constructed by superposing a plu-

rality of single-layer roof coverings in the manner indicated by Figure 3, it being of course preferable to stagger the joints between adjacent units in the respective layers of the multiple-ply roof and to bond the layers of such a roof to each other with a suitable binder or cementing agent. Obviously, the end portions of the strip or sheet units may be formed with cooperating tongue and groove elements in a manner and for a purpose identical with that described in connection with the long margins of said units.

Since many changes, variations, and modifications in the specific form, construction, and relation of the elements shown and described may be had without departing from the spirit of my invention, I wish to be understood as being limited solely by the scope of the appended claims, rather than by any details of the illustrative showing and foregoing description.

I claim as my invention:

1. Roofing material comprising plane units of flexible, felted material, each of said units being formed with a tongue portion of reduced thickness along one margin and a complementary, laterally-opening groove along its other margin, said groove being defined between separable flaps each susceptible of being bent into substantially perpendicular relation with the plane of its unit to fully uncover the inner face of its associated flap.

2. Roofing material comprising plane units of flexible, felted material each formed with a laterally and outwardly tapered tongue portion along and forming one of its margins, a laterally and inwardly tapered, complementary groove along and opening through the other unit margin, and separable flaps, each susceptible of being bent into substantially perpendicular relation with the plane of the unit to fully uncover the inner face of the associated flap, defining said groove.

3. Roofing material comprising plane units of flexible, felted material each formed with a laterally and outwardly tapered tongue portion along and forming one of its margins, a laterally and inwardly tapered, complementary groove along and opening through the other unit margin, and separable flaps, each having such thickness at its junction with the unit body as will permit of its being bent into substantially perpendicular relation therewith to fully uncover the inner face of the associated flap, defining said groove.

4. In flexible, felted roofing material, means for interconnecting adjacent units of the material in a weather-proof joint having a thickness substantially equal to that of the body portion of the material, said means comprising a relatively-deep, inwardly tapered groove longitudinally along and opening marginally through one edge of the material to form spaced, cooperating, separable flaps of such thickness adjacent their junction with the unit body portion as will permit of their being individually bent into substantially perpendicular relation with the unit body portion to fully uncover the inner face of the associated flap, and a correspondingly and outwardly tapered tongue portion of reduced thickness longitudinally along and forming the opposite margin of each unit of the material and adapted for engagement and sealing between the groove flaps of an adjacent unit of the material.

JAMES MELVILLE FERGUSON.
